Fraenzel and Richards.

UNITED STATES PATENT OFFICE.

FREDERICK EISENHUT, OF IRVINGTON, NEW JERSEY.

SHAVING-BRUSH.

1,356,134.

Specification of Letters Patent.

Patented Oct. 19, 1920.

Application filed July 19, 1919. Serial No. 311,955.

To all whom it may concern:

Be it known that I, FREDERICK EISENHUT, a citizen of the United States, residing at Irvington, in the county of Essex and State 5 of New Jersey, have invented certain new and useful Improvements in Shaving-Brushes; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification.

15 The present invention relates, generally, to improvements in shaving brushes; and, the present invention has reference, more particularly, to a novel means of positively securing the ferrule of the brush to the butt-end of the brush-handle without the use of cement or other fastening means, as heretofore, the said securing or fastening means serving at the same time as a carrier for a 20 face-massaging attachment, if such attachment is desired for use with the brush.

25 The present invention, therefore, has for its principal object to provide a novel and simply constructed fastening means for attaching the ferrule containing the usual bunch of bristles about the butt-end of the handle, so that the parts will be securely held by clamping action against turning or disconnection, and to provide a means for dispensing, if desired, with the usual means of cementing or otherwise securing the ferrule upon the butt-end of the handle.

30 The invention has for its further object to provide in connection with a shaving brush and the securing means above stated, a novel and simple construction for attaching to one side of the brush-ferrule, a massaging device; and, the invention has for a still further object a novel arrangement and 35 novel construction of guard which will prevent the possibility of soap and water getting upon the massaging fingers of the device, to contaminate the same with foreign matter, or destroying the usefulness of the 40 device, and also to serve as a means of preventing the water running down the brush, upon the ferrule of the same, and then upon 45 the fingers of the operator.

50 Other objects of the present invention not 55 at this time more particularly enumerated

will be clearly understood from the following detailed description of the present invention.

The present invention consists, therefore, in the novel shaving brush more particularly 60 set forth in the following specification; and, the invention consists, furthermore, in the novel arrangements and combinations of the several devices and parts, as well as in the details of the construction of the said parts, 65 all of which will be more fully described in detail in said specification, and then finally embodied in the clauses of the claim which are appended to and which form an 70 essential part of the said specification.

The invention is clearly illustrated in the accompanying drawings, in which:—

75 Figure 1 is a view, partly in elevation and partly in vertical section, of a combined shaving brush and massaging device, showing one embodiment of the principles of the present invention, and Fig. 2 is a horizontal section of the same, said section being taken on line 2—2 in said Fig. 1.

80 Fig. 3 is a view, partly in elevation and partly in vertical section, of a modified form of shaving brush, provided with a ferrule-securing device made according to and embodying the principles of the present invention.

85 Similar characters of reference are employed in all of the said above described views, to indicate corresponding parts.

90 Referring now to the several figures of the drawings, the reference-character 1 indicates a suitable brush, such as a shaving brush, and which is provided with a handle 2 and a connecting ferrule 3 of metal, as indicated in Figs. 1 and 2 of the drawings, or 95 a hard rubber or similar ferrule 4, as shown in Fig. 3. In said Figs. 1 and 2, the said handle is made with the usual butt-end 5, upon which the ferrule 3 is mounted by being slipped over said butt-end, the said ferrule being of such length, so that a space or 100 chamber 6 will be provided between the end-surface of the butt-end 5 of the handle, and the end-surface of the butt-end 8 of the brush of bristles 7 inserted in the ferrule 3 105 and secured therein in the usual manner. Surrounding the upper portion of said ferrule, and the usual marginal bead 9 of the same, is a ring-shaped guard 10, said guard being formed with a marginal annular pro- 110

jection or extension, as 11, the inner surface of which tapers outwardly, as at 12, so as to provide, as will be seen from an inspection of Fig. 1 of the drawings, above said 5 bead 9, an annular receiving depression 13 for catching any water or soap-suds from the bunch of bristles, when using the shaving brush. This guard is usually made of soft rubber so as to be easily forced over the 10 end of the ferrule, being held in place by frictional contact with the ferrule, and being readily removed from the ferrule for cleansing purposes.

The said guard may, if desired, be provided with an extension 14, formed with a 15 hole or perforation 15, said extension extending downwardly and lying close to the outer surface of the ferrule, and the said hole or perforation 15 being in alinement 20 with a hole or perforation 29 in the side of the ferrule 3.

The previously mentioned massaging device, which is detachably mounted upon one side of the shaving brush, comprises a base- 25 plate 16 placed upon the end-face of the butt-end of the handle 2, said plate being secured to said butt-end by means of a screw 17, or other suitable fastening means, and having an upwardly extending and perforated flange 30 18, said base-plate 16 and its flange 18 having sufficient resiliency so that it will be slightly bowed in an outward direction toward the interior surface of the ferrule, when the various parts, to be presently described, are in their assembled relation, so as to serve as an anchor or binding member to securely clamp the ferrule in its position upon the butt-end of the handle, as will be clearly understood from an inspection of the 35 several figures of the drawings. The perforation in said flange 18 is in alinement with the perforations in the ferrule 3 and in the extension 14 of the guard 10, a screw-threaded bolt 19 being passed through the 40 several perforations in said flange 18, the ferrule 3, and said extension 14. To prevent turning of the said bolt, when the several parts are tightened in their assembled relation, the head 20 of said bolt, which is 45 placed directly above the base-plate 16 and against the flange 18, is preferably of elongated shape, as shown. Upon the extending and screw-threaded shank-portion of said bolt 19 are mounted and screwed thereon, a 50 soft rubber washer 21, a tightening nut 22, and an enlarged disk-shaped member or element 23, the parts being finally and firmly secured in place by an additional nut 24, substantially as shown in Fig. 2 of the drawings. 55 Embracing the marginal edge-portion of said disk-shaped element 23, and suitably secured about said edge-portion, is the recessed portion 26 of a cup-shaped massaging member or element 25, made of soft rubber or other analogous material, and its

main body-portion having extending therefrom a multiplicity of massaging fingers, as 27.

From an inspection of said Figs. 1 and 2, it will readily be understood, when the several devices and parts have been secured in their assembled relation, and properly and firmly tightened, that the end-edges 28, of the previously mentioned flange 18, as said flange is bowed, will firmly bear upon the 75 inner surface of the ferrule 3, and the latter having sufficient resiliency, the result will be that the slight distortion of the ferrule will cause it to become firmly bound to the butt-end 5 of the handle 2, so that the brush- 80 handle will at all times be tight, and with the constant use of the brush there will be no loosening or disassembling of the various parts.

The anchoring device may also be used 85 with shaving brushes in which the ferrule is internally screw-threaded, as at 29, and is screwed upon an externally screw-threaded butt-end 30 of a handle 31, as shown in Fig. 3 of the drawings.

The anchoring means, as well as the massaging member, and the various parts for securing said elements in their assembled relation, is the same as that herein-above described in connection with the construction 95 illustrated in Figs. 1 and 2 of the drawings, and any further description of the same is therefore deemed unnecessary.

From the foregoing description, and from an inspection of the figures of the drawings, 100 it will be clearly evident, that the guard 10 may be omitted, if desired. The massaging element, in some instances, may also be omitted, in which case simply the anchoring device, with its bolt 19 and corresponding 105 tightening nut are employed.

I am fully aware, therefore, that some changes may be made in the general arrangements and combinations of the various devices and parts, as well as in the details 110 of the construction of the same, without departing from the scope of the present invention as set forth in the foregoing specification. Hence, I do not limit my present invention to the exact arrangements and combinations of the various devices and parts as described in the said specification, nor do I confine myself to the exact details of the construction of the said parts, as illustrated in the accompanying drawings.

I claim:—

1. A shaving brush comprising a handle having a butt-end, a ferrule upon said butt-end, an anchoring means within said ferrule having a portion located upon said butt-end, and having another portion bearing against the inner surface-portion of the ferrule, means connected with the first-mentioned portion of the anchoring means for securing the same upon said butt-end, and means con- 130

nected with the second-mentioned portion of the anchoring means for causing a binding action between said second-mentioned portion of the anchoring means and the 5 inner surface-portion of the ferrule.

2. In a shaving brush, in combination, with a handle having a butt-end, a ferrule mounted upon said butt-end, said ferrule being provided in its side with a perforation, 10 and an anchoring means comprising a base-plate, means for securing said plate upon said butt-end, said base-plate having a perforated flange, the end-edges of said flange bearing in engagement upon the inner surface-portion of said ferrule, a tightening bolt connected with said flange, said bolt extending through the perforation in said flange and also through the perforation in said ferrule, and means upon that portion 15 of the bolt extending beyond the outer surface of said ferrule for causing a binding action between the end-edges of the flange and the inner surface portions of said ferrule.

25 3. In a shaving brush, in combination, with a handle having a butt-end, a ferrule mounted upon said butt-end, and an anchoring means comprising a base-plate, means for securing said plate upon said butt-end, 30 said base-plate having a perforated flange, the end-edges of which bear in engagement upon the inner surface-portion of said ferrule, a tightening bolt connected with said

flange and extending through said ferrule, and means upon said bolt for causing a binding action between the end-edges of the flange and the said ferrule, and a massaging element mounted upon said bolt. 35

4. In a shaving brush, in combination, with a handle having a butt-end, a ferrule 40 mounted upon said butt-end, said ferrule having a perforation in its side, and an anchoring means comprising a base-plate, means for securing said base-plate upon said butt-end, said butt-end having a perforated 45 flange, the end-edges of which bear in engagement upon the inner surface-portion of said ferrule, a tightening bolt mounted in the perforation of said flange and extending through the perforation in said ferrule, a 50 head upon said bolt bearing against said flange, a washer and tightening nut upon the projecting portion of said bolt, a disk-shaped element also mounted upon said bolt, an auxiliary nut for tightening said disk-shaped element in place, and a massaging member provided with finger-like extensions 55 mounted upon said disk-shaped element.

In testimony, that I claim the invention set forth above I have hereunto set my hand 60 this 17 day of July, 1919.

FREDERICK EISENHUT.
